attorney.

UNITED STATES PATENT OFFICE.

ALBERT KLEIN, OF EMSWORTH, PENNSYLVANIA.

MONKEY-WRENCH.

1,180,301.

Specification of Letters Patent. Patented Apr. 25, 1916.

Application filed June 11, 1913. Serial No. 772,992.

To all whom it may concern:

Be it known that I, ALBERT KLEIN, a citizen of the United States, and a resident of Emsworth, in the county of Allegheny and State of Pennsylvania, have invented a new and useful Improvement in Monkey-Wrenches; and I do hereby declare the following to be a full, clear, and exact description thereof.

10 My invention relates to wrenches and has special reference to such a class as are known as monkey wrenches, for bearing against flat surfaces to turn the same.

15 The object of my invention is to provide a cheap, simple and efficient form of monkey wrench which can be adjusted to any gage in a second's time and when so adjusted will be firm and secure and will not become loose until desired by the person 20 using the same.

A further object is to provide a wrench having few parts in order to eliminate the labor of assembling and finishing the same.

25 My invention consists, generally stated, in the novel arrangement, construction, and combination of parts as hereinafter more specifically set forth and described and particularly pointed out in the claims.

30 To enable others skilled in the art to which my invention appertains to construct and use my improved monkey wrench, I will describe the same more fully referring to the accompanying drawing in which:—

35 Figure 1 is a side elevation of my improved wrench showing part of the same broken away. Fig. 2 is a similar view of the same showing the jaws closed and the locking piece in its open position. Fig. 3 40 is a top plan view of the wrench with part of the sliding jaw broken away. Fig. 4 is a top plan view of the sliding jaw showing the rack by which the same is locked. Fig. 5 is an end view of the locking piece employed. Fig. 6 is a top view of the spring used for engaging with the locking piece.

Like symbols of reference herein indicate like parts in each of the figures of the drawing.

50 As illustrated in the drawing my improved wrench has a body member 1 which is provided with a fixed jaw 2 at the one end of the same and a handle portion 3 at its other end. This body member 1 has a pair 55 of walls 4 which extend up from the fixed jaw 2 and are provided with countersunk

holes 5 at the upper end of the same for the purpose of receiving rivets 6, which rivets extend through holes 7 in a fixed pawl 8 which fits between the walls 4 of said body member. The pawl 8 has its lower face 9 curved as shown in Fig. 1 and such face terminates at its rear end in a tooth 10 as hereinafter described.

Immediately beyond the two walls 4 and at a lower level than the bottom of said walls are a pair of small flanges 11 which define a recess 12 wherein is disposed a locking dog 13. This locking dog 13 is adapted to be held in position in the recess 12 by means of a pin 14 extending through the lower end of such locking dog and through holes 15 in each of the small flanges 11, while the free end of said dog is provided with a lateral operating arm or 75 trunnion 16 at each side of the same as later explained. The locking dog 13 is further provided with a small shoulder 17 on the outer face of the same for engaging with a flat spring 18 secured to the handle 80 portion 3 of said body member. This spring 18 has a curved end portion 19 for fitting against the shoulder 17 of the locking dog so that the tendency of such spring is to keep the said dog in an upright position 85 such as shown in Fig. 1 of the drawing.

The sliding jaw 20 has a shank 21 which is slidable between the walls 4 of the body member 1 and is provided with a rack 22 upon its outer face for engaging with the 90 tooth 10 on the pawl 8 as later described. The space included between the walls 4 is of sufficient height to permit the rear portion of the shank 21 to have its rack 22 disengaged from the tooth 10 on the under face 95 of the pawl 8 while the other end of the same included between said walls will be held to a substantially firm position as shown in Figs. 1 and 2.

The use and operation of my improved 100 monkey wrench are as follows:—The wrench is grasped by the handle portion 3 and the thumb pressed against one of the trunnions or operating arms 16 of the locking dog 13 so as to draw this member downward 105 from its engagement with the bottom face of the shank 21 of the sliding jaw 20. This movement allows the tooth 10 on the under face of the pawl 8 to become disengaged from the rack 22 whereupon the said bar 110 may be pushed to any desired position in order to get the necessary distance between

the jaws 2 and 20 and when this is done the thumb is removed from the member 16 and the spring 18 raises the locking dog 13 to its original position in order to again engage 5 the tooth 10 with the desired tooth on the rack 22 thereby locking the same and preventing any further movement of the sliding jaw 20.

It will thus be seen that my improved 10 wrench will be quick operating and effective and as the parts may all be drop-forged, the machine work will be reduced to a minimum so that the cost of the wrench will be considerably lower than the present cost 15 of less efficient wrenches.

Various modifications and changes in the design and construction of my improved wrench may be resorted to without departing from the spirit of the invention or sacrificing any of its advantages.

What I claim as my invention and desire to secure by Letters Patent is:—

1. A wrench including a body member, a fixed jaw formed on the body member, a pawl carried by the fixed jaw, a movable jaw having its shank disposed for sliding movement through the fixed jaw and provided with rack teeth engageable with the pawl, and a spring pressed locking dog 25 pivotally mounted in the body member and a locking means formed on the dog, said means being normally held in locking engagement with the shank of the movable jaw for maintaining the shank in spaced relation 30 to the body member and in locking engagement with the pawl, said locking means being supported upon the face of the body member when in operative position.

2. A wrench of the character described 40 including a body member, a fixed jaw car-

ried by the body member, a movable jaw 45 slideable through the fixed jaw, a fixed pawl carried by the fixed jaw and engageable with the movable jaw for maintaining the movable jaw in adjusted position, a locking dog adapted to engage with the movable jaw for maintaining the same in engagement with the pawl, and a lateral trunnion carried by the locking dog, said trunnion being engageable with the body member for limiting 50 the swinging movement of the dog and constituting a finger grip by which the dog may be manipulated.

3. A wrench of the character described 55 including a body member, a fixed jaw formed thereon, a pair of parallel spaced flanges formed on one longitudinal face of the body member, a movable jaw slideable with respect to the fixed jaw, a pawl carried by the fixed jaw and engageable with the shank of the movable jaw for maintaining 60 the movable jaw in adjusted position, a locking dog pivotally mounted between the said flanges, a leaf spring engaging the dog for normally maintaining the dog in engagement with the shank of the movable jaw for urging the same into locking engagement with the pawl, and lateral trunnions formed on the outer terminal of the locking dog, said trunnions constituting finger grips for 65 manipulating the dog and being engageable with the longitudinal face of the body member for limiting the movement of the dog in both active and inactive positions.

In testimony whereof, I, the said ALBERT 70 KLEIN, have hereunto set my hand.

ALBERT KLEIN.
